UNITED STATES PATENT OFFICE

158,989

COMBINED CABINET STOVE AND TABLE

Howard McNaughton, Kalamazoo, Mich.

Application September 25, 1947, Serial No. 141,577

Term of patent 3½ years

(Cl. D33—19)

To all whom it may concern:

Be it known that I, Howard McNaughton, a citizen of the United States, residing at the city and county of Kalamazoo, State of Michigan, have invented a new, original, and ornamental Design for Combined Cabinet Stove and Table, of which the following is a specification, reference being had to the accompanying drawing, forming part thereof, in which:

Fig. 1 is a front perspective view, and

Fig. 2 is a rear perspective view of a combined cabinet stove and table, showing my new design.

I claim:

The ornamental design for a combined cabinet stove and table, as shown.

HOWARD McNAUGHTON.
